UNITED STATES PATENT OFFICE.

JENSHIRO TERUYA, OF CONEY ISLAND, BROOKLYN, NEW YORK.

AMUSEMENT APPARATUS.

Application filed January 10, 1923. Serial No. 611,780.

To all whom it may concern:

Be it known that I, JENSHIRO TERUYA, a subject of the Emperor of Japan, residing at Coney Island, Brooklyn, in the county of Kings and State of New York, have invented new and useful Improvements in Amusement Apparatus, of which the following is a specification.

This invention relates to an amusement apparatus and particularly to an apparatus adapted to be controlled by a number of contestants and wherein by the exercise of skill one of the contestants will cause the apparatus to be operated so as to visually or otherwise suitably indicate and determine the successful contestant.

An essential object of the invention is to provide an apparatus of this character including a number of movable figures and means for imparting lifelike movements to the figures and for causing movements of the figures to be transmitted to an indicator which operates to determine and indicate the first or successful contestant to control the particular figure toward an end in view which will be apparent from reference to the description herein contained.

Another object of the invention is to provide a skill controlled apparatus designed particularly for use in amusement parks, fairs or similar public places and which will include instrumentalities serving to furnish considerable amusement and to require a fair measure of skill in the successful operation thereof.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a front view of the apparatus.

Figure 2 is a vertical section on line 2—2 of Figure 1.

Figure 3 is a vertical section through the indicating mechanism.

Figure 4 is a front view of the indicating mechanism showing a diagram of the circuit.

Figure 5 is a view in rear elevation of one of the swings.

Figure 6 is a section through a portion of one of the figures.

In carrying the invention into practice, I

use a counter 5 to one side of which swings 6 in longitudinal alignment are hung, each mounted to oscillate from a bar 7 and provided at its upper end with an arm 8. For each swing 6 is a controlling mechanism 9 consisting of a large sprocket gear 10 supported at one side of the counter 5 in a bracket 11. The shaft 12 of the gear is provided with a long lever 13 having a handle 14 exposed from above the counter 5. When the lever 13 is oscillated by hand, the gear 10 is placed in motion. A sprocket chain 15 passes over the gear 10 and as illustrated one end 16 of the chain is secured to the sprocket. The chain passes under an idler sprocket 17; under a similar sprocket 18 and thence over a sprocket 19 and the terminal end 20 of the chain is secured to a flexible connection 21 with the arm 8 at the upper end of the swing 6. It follows from this construction, that the chain 15 may be reciprocated when the lever 13 is oscillated and that due to these reciprocations of the chain, swinging motions are imparted to the swing 6.

Seated in each of the swings 6 is a doll figure 22 having jointed legs 23. The legs 23 at the knee are connected to the body of the doll by springs 24 which normally serve to hold the legs in straight positions as shown in full lines in Figure 6. The side bars of each swing are provided with actuating wires 25 connected at their lower ends to the legs 23 at one side of the joints thereof so that when pull is applied to the wires 25, the legs will be moved against the tension of the springs 24. In order to make this movement automatic while the swing is in motion, I extend the wires 25 upward to the top of the swing and loop the same at 26 over the connection 21. When the swing is in its neutral position shown in Figure 2, a pull upon the connection 21 at its connection with the loop 26 creates slack therein. At this time the springs 24 act to project the legs 23 straight forward. When the chain 15 is operated by actuations of the lever 13 the slack in the connection 21 is removed. This places the wires 25 under tension and pulls upon the same so as to bend the legs 23 downward upon their joints and move same against the action of the springs 24. In this manner I am able to set up lifelike movement of the figure when the swing 6 is in motion.

For each of the swings is an indicating

mechanism designed to be actuated by the Figure 22 in movements of the swing 6. This mechanism consists of a fixed dial 27 suitably numbered at 28 and provided with 5 an arbor 29 on which a relatively large ratchet wheel 30 is fixed. The dial is stationary with respect to the arbor and the latter is provided with a pointer 31 co-acting with the numbers of the dial.

10 A member 32 is mounted adjacent to the ratchet wheel 30 and same is provided with a dog 33 co-acting with the ratchet wheel so as to move same in one direction. To prevent retrograde rotation of the ratchet wheel, I provide a co-acting dog 34 engageable with the teeth thereof as the ratchet wheel revolves. The member 32 is supported from a leaf spring or yieldable device 35 disposed in the path of movement 15 of the legs 23 of the figure object 22 so as to be kicked thereby when the swing is at the limit of its forward motion. This imparts a hammer like action to the spring upon successive movements of the swing to 20 forward positions and in consequence thereof the dog 33 is actuated so as to turn the ratchet wheel 30 and cause the pointer 31 to cycle around the dial and co-act with the pointer 31 thereof.

25 The dial 27 and co-acting pointer 31 constitute visual means for determining to a number of contestants the successful contestant who first causes the pointer 31 of a particular dial of the apparatus to make 30 a complete revolution upon its dial.

35 In order to provide a second visual or otherwise suitable means of indicating the successful contestant, I provide a circuit closer 36 consisting of a yieldable contact member 37 in the path of movement of the pointer 31 and adapted to co-act a second contact member 38. Both of these contact members are operatively arranged in a lamp circuit 39 wherein a lamp 40 is arranged 40 above the dial 27 as clearly shown in Figures 1 and 4 of the drawings.

45 In operation the contestants standing in front of the counter 5 grasp the handles 14 of the respective members 13 moving same to and fro. This places the swings 6 under individual control of the contestants. By giving uniform slow movements to the levers 14 the objects or figures 22 are 50 made to ascend to their maximum heights and in consequence thereof the legs 23 are made to kick the springs 35. This accordingly actuates the respective pointers 31 and according to the measure of skill employed, invites an operation of one of the pointers 55 in advance of all of the others.

60 While I have described what I deem to be the most desirable embodiment of my invention, it is obvious that many of the details may be varied without in any way departing from the spirit of my invention,

and I therefore do not limit myself to the exact details of construction herein set forth nor to anything less than the whole of my invention limited only by the appended claims.

70

What is claimed as new is:—

1. An amusement apparatus comprising an indicator, an object swingingly movable with respect to the indicator, the indicator including means to be engaged by the object to govern actuations of the indicator, and means for operatively moving the object. 75

2. An amusement apparatus comprising an indicator, including a numbered dial and revolving co-acting pointer, a circuit closer co-acting with the pointer, an object swingingly movable with respect to the indicator and adapted to actuate the same and means for moving the object. 80

85 3. A amusement apparatus comprising a figure having jointed limbs, an indicator having a revolving pointer associated with a dial an actuating portion disposed in co-acting relation to the figure, and means for moving the limbs of the figure to bring same in operating contact with said actuating portion of the indicator. 90

4. An amusement apparatus comprising a movably mounted figure having jointed limbs, an indicator having an actuating portion disposed in co-acting relation to the figure, and means for moving the figure to bring the limbs in operating contact with said actuating portion of the indicator. 95

100 5. An amusement apparatus comprising a plurality of swingingly movable objects, operating means for moving each of said objects, and an indicator for each object, said indicator including means co-acting with the object so that on certain movements of the object with respect to the means of the indicator, the latter will be actuated. 105

110 6. An amusement apparatus comprising a swing, an object seated in the swing and provided with jointed limbs, means for moving the swing and for actuating the limbs of the object, an indicator disposed in the path of movement of the swing and co-acting with the limbs of the object to control 115 actuations of the indicator.

120 7. An amusement apparatus comprising a swing, an object seated in the swing, means for moving the swing, and indicator means co-acting with the object to govern actuations of the indicator upon the actuation of said first means.

125 8. An amusement apparatus comprising a swing, an object seated in the swing, means for moving the swing, and indicator means co-acting with the object to govern actuations of the indicator upon the actuations of said first means, the swing moving means including a reciprocating connection co-acting with the swing, the object having jointed 130

limbs, and means actuated by said connection for moving the limbs of said object.

9. An amusement apparatus comprising a swingingly movably supported object, 5 means for moving the object, and an indicator having an actuating portion adapted to co-act with said object and disposed in the path of movement thereof.

10. An amusement apparatus comprising 10 a plurality of movable objects, means for individually controlling movements of the objects, and an indicator for each of said objects and disposed in the path of movement thereof correlated therewith to be actuated thereby upon the actuation of said means, and including a fixed numbered dial and revolving pointer co-acting with the dial.

11. In an amusement apparatus comprising 20 a plurality of movable objects, means for individually controlling movements of the objects, and an indicator for each of said objects and disposed in the path of

movement thereof, said indicator including a ratchet means operable by said object, a 25 fixed dial, and a pointer co-acting with said dial and operable by said ratchet means.

12. An amusement apparatus including a movably mounted object, controlling mechanism for moving the object, an indicator 30 correlated with the object and including a dial, a pointer revolving on the dial, and means operable by said moving object for operating the pointer.

13. An amusement apparatus comprising 35 a movably mounted object having jointed limbs, means for normally holding said jointed limbs in a broken condition, an indicator, and means for moving the object into operating engagement with the indicator 40 and for simultaneously moving the limbs of the object to close the joint.

In testimony whereof I have affixed my signature.

JENSHIRO TERUYA.
